(57) **CLAIM**

The ornamental design for an enclosure for a radio frequency transceiver, as shown and described.

DESCRIPTION

FIG. 1 is a perspective view of the top, right and front side of an enclosure for a radio frequency transceiver, showing our new design;

FIG. 2 is a top plan view thereof;

FIG. 3 is a bottom plan view thereof;

FIG. 4 is a right side elevation view thereof;

FIG. 5 is a front side elevation view thereof;

FIG. 6 is a rear side elevation view thereof; and,

FIG. 7 is a left side elevation view thereof.

The broken lines shown in FIG. 4—FIG. 7 are included for the purpose of illustrating environmental structure only and form no part of the claimed ornamental design.
